VAPORIZER

Walter R. Kuzmin, Nutley, and Samuel J. Levine,
Newark, N. J.

Application October 2, 1947, Serial No. 777,418

9 Claims. (Cl. 219—38)

1

This invention relates to vaporizers of the type and kind employing an electric heating element for heating water or other fluid to generate vapor for discharge of a medicated or other vapor from the device. More particularly, the invention deals with a device of the character described, which is so designed as to provide substantially instantaneous generation of vapor for quick and continued supply of the medicated or other vapors, thereby producing an efficient and economical type of device of the kind under consideration.

The novel features of the invention will be best understood from the following description, when taken together with the accompanying drawing, in which certain embodiments of the invention are disclosed and, in which, the separate parts are designated by suitable reference characters in each of the views and, in which the drawing is a sectional view through a device made according to our invention with part of the construction broken away.

In illustrating one adaptation and use of our invention, we have shown the same applied to a jug or vessel having an insulated wall such as the commonly known "Thermos" jugs for the purpose of holding a fluid temperature and, thus, minimizing the electric consumption in a prolonged operation of the device. In many instances, vaporizers of the kind under consideration are used for medicinal purposes for a continued or lengthy discharge of a medicated vapor to ease congested conditions, such as asthma, head colds, hay fever, sinus trouble and the like. On the other hand, the apparatus may be also utilized for the discharge of various insecticides for the treatment of clothing in a closet or, on the other hand, to generally treat or condition a room or compartment for any purpose whatever.

In the drawing, 10 represents the jug or container of a large "Thermos" device, the walls of which are constructed from inner and outer wall portions 11 and 12 with suitable insulating material 13 therebetween. The upper end of the jug or container has a large upwardly extending neck 14 integral with the wall structure thereof and treated, as seen at 15, to receive a detachable cap 16, which forms the mounting part of my improved vaporizing attachment. In other words, a vessel can be constructed solely for the intended purpose or a conventional standard "Thermos" jug can be converted by substitution of the adaptor cap 16 for the present closure cap in using the same as a vaporizing device. Secured centrally to the upper surface of the cap is a

2

plate 17, having a housing portion 18, in which is a socket 19. In the socket 19 is disposed two electric terminals, one of which is shown at 20, for placing the electric heating element 21 in circuit with an electric source of supply. Adjacent the casing 18 is a small steam or vapor chamber 22 having a tube 23 secured in the lower wall thereof and extending through the plate 17 and through the cap 16, as well as an insulating plug 24 disposed upon the inner surface of the cap 16. The plug 24 has two bores 25 and 26; the pipe or tube 23 extends into one bore and the electric wires, one of which is shown at 27, extends from the terminal pins 20 through the bore 26 and contacting with the heating element 21.

Arranged in the bore 25 is a governor or control thimble or sleeve 28, having a steam inlet, as at 29, and a condensation discharge, as at 30, the latter being disposed at the lower end of said thimble. If desired, two of the inlets 28 may be employed, but only one will appear in the sectional view shown.

Arranged upon the plug 24 is a long tube or cylinder 31, which forms a steam generating cylinder and extends well into the jug or container 10 to such a degree as to be exposed to a relatively large part of water or other fluid disposed in said jug or container.

At the lower end of the cylinder 31 is a plug 32 of insulating material forming a support for the lower end of the heating element 21, as seen at 33, the plug also having a port 34 for admission of fluid into the cylinder 31 to a level common to the level of fluid as contained in the jug or container 10, which level of fluid is indicated at 35.

Detachable with respect to the top of the chamber 22 is a cap 36 having attached to the inner surface thereof a chain 37, from which is suspended a perforated medication or other container 38. Secured to and extending outwardly from the chamber 22 is a discharge spout or nozzle 39.

In the use of the device, the jug or container 10 is partially filled with water or other fluid, after which the vaporizer attachment, as a complete unit, is attached to the jug in the manner shown. The container 38 is filled with the suitable crystal or other medications, or other type of material, to be used in conjunction with the device and, after which, the socket of an extension cord, from a source of supply, is connected with the plug pins 20 to heat the element 21. The element may be of any type or kind, but a carbon heating element is preferred. In a matter of from ten to fifteen

seconds the water or fluid within the cylinder 31 becomes heated sufficiently to generate steam or vapor, which rises in the cylinder and is passed through the port or ports 29 and, thus, up into the chamber 22 around the container 38, where it picks up the medication and the vapor is then discharged through the nozzle 39. Any condensation that may collect will drain back into the cylinder 31 through the port 30. With a relatively large body of fluid, we have found that a device of this type and kind can operate for many hours at a nominal electric consumption and without any danger of overheating and with the continued ejection of vapor from the nozzle for any purpose for which the device is used. The discharge of medicine has proved to be very desirable from the standpoint of giving comfort to those suffering from the ailments of the general type and kind mentioned heretofore. On the other hand, various insecticides and other types of chemicals can be utilized for vapor discharge from the device for the treatment of moths and other house pests or insects; whereas the device may be used for purification and/or otherwise treating a room or compartment for counteracting objectionable odors and similar purposes. In referring to fluid, it will be understood that the fluid itself may comprise a pre-prepared solution having properties which are suitable for the intended purpose. In the latter instance, the use of the container 38 or a chemical of some type or kind therein may be optional.

In vaporizers of the kind under consideration, one of the objectionable features has been the long time required for generation of vapors. This has been quite a nuisance or annoyance to the user. One of the distinctive features of our invention resides in the fact that a substantially instantaneous generation of vapor is provided and this is largely due to the relatively restricted cylinder and the use of a heating element which can be active immediately upon the small body of fluid within the cylinder, without, in any way, materially changing the temperature of the remainder of the fluid in the container or vessel.

We have found from experience that, while the fluid in the cylinder 31 is sufficiently hot to generate the steam vapors, the fluid in the container or jug would be hardly warm to the touch, at least after a short use of the device. In time, the fluid in the jug will be heated to a greater extent but this heating really adds to the efficiency of operation of the device.

Having fully described our invention, what we claim as new and desire to secure by Letters Patent is:

1. A vaporizer comprising a fluid container, a vaporizing unit detachable with respect to the container, said unit comprising a cap for mounting on and forming a closure for the container, a steam generating cylinder on the inner surface of the cap and adapted to extend into the container, an electric heating element mounted in the cylinder in spaced relation to the walls thereof, means on the cap for placing the electric heating element in circuit with a source of electric supply, a vapor chamber on said cap, means placing said chamber in communication with the upper end of said cylinder, said chamber having a discharge spout, and means detachable with respect to said chamber for supporting material in and in spaced relation to the walls of the chamber for exposure to the vapor therein.

2. A vaporizer comprising a fluid container, a vaporizing unit detachable with respect to the

5 container, said unit comprising a cap for mounting on and forming a closure for the container, a steam generating cylinder on the inner surface of the cap and adapted to extend into the container, an electric heating element mounted in the cylinder in spaced relation to the walls thereof, means on the cap for placing the electric heating element in circuit with a source of electric supply, a vapor chamber on said cap, means placing said chamber in communication with the upper end of said cylinder, said chamber having a discharge spout, means detachable with respect to said chamber for supporting material in and in spaced relation to the walls of the chamber for exposure to the vapor therein, said last named means comprising a cover, and a perforated container flexibly supported in connection with said cover.

3. A vaporizer comprising a fluid container, a vaporizing unit detachable with respect to the container, said unit comprising a cap for mounting on and forming a closure for the container, a steam generating cylinder on the inner surface of the cap and adapted to extend into the container, an electric heating element mounted in the cylinder in spaced relation to the walls thereof, means on the cap for placing the electric heating element in circuit with a source of electric supply, a vapor chamber on said cap, means placing said chamber in communication with the upper end of said cylinder, said chamber having a discharge spout, means detachable with respect to said chamber for supporting material in and in spaced relation to the walls of the chamber for exposure to the vapor therein, said last named means comprising a cover, a perforated container flexibly supported in connection with said cover, said container having insulated walls, and means insulating the mounting of the electric heating element at opposed ends of said cylinder.

4. A vaporizing device of the character described comprising a fluid container, an elongated narrow cylinder, means detachably mounting the cylinder to extend into said container, said last named means including a casing forming a vapor chamber, a perforated thimble shaped member controlling transmission of vapor from the upper end of the cylinder to said chamber, means including insulating plugs at opposed ends of the cylinder for mounting an electric heating element in the cylinder in spaced relation to the walls thereof, the lower plug having an aperture for admitting fluid of the container into said cylinder, means adjacent said casing for supporting electric terminals in circuit with said heating element to establish electric communication with a source of electric supply, said casing have a detachable cover, a perforated container supported on said cover within the vapor chamber and in spaced relation to the walls of said casing, and a discharge on the casing adjacent the upper end thereof through which vapors from said chamber are adapted to pass.

5. A vaporizing device of the character described comprising a fluid container, an elongated narrow cylinder, means detachably mounting the cylinder to extend into said container, said last named means including a casing forming a vapor chamber, a perforated thimble shaped member controlling transmission of vapor from the upper end of the cylinder to said chamber, means including insulating plugs at opposed ends of the cylinder for mounting an electric heating element in the cylinder in spaced relation to the walls thereof, the lower plug having an aperture

for admitting fluid of the container into said cylinder, means adjacent said casing for supporting electric terminals in circuit with said heating element to establish electric communication with a source of electric supply, said casing having a detachable cover, a perforated container supported on said cover within the vapor chamber and in spaced relation to the walls of said casing, a discharge on the casing adjacent the upper end thereof through which vapors from said chamber are adapted to pass, and said first named means comprising a cap in threaded engagement with said container.

6. A vaporizing device of the character described comprising a fluid container, an elongated narrow cylinder, means detachably mounting the cylinder to extend into said container, said last named means including a casing forming a vapor chamber, a perforated thimble shaped member controlling transmission of vapor from the upper end of the cylinder to said chamber, means including insulating plugs at opposed ends of the cylinder for mounting an electric heating element in the cylinder in spaced relation to the walls thereof, the lower plug having an aperture for admitting fluid of the container into said cylinder, means adjacent said casing for supporting electric terminals in circuit with said heating element to establish electric communication with a source of electric supply, said casing having a detachable cover, a discharge on the casing adjacent the upper end thereof through which vapors from said chamber are adapted to pass said first named means comprising a cap in threaded engagement with said container, the container having insulated walls, and the cover of said casing having a flexibly supported perforated container adapted to be suspended within the chamber of said casing.

7. A vaporizer of the class described comprising a large fluid container, a cap detachable with said container, means comprising an elongated tube mounted centrally of the cap and extending into said container forming an elongated restricted fluid chamber in said container, means on the cap and extending into said tube for electrically heating fluid in said chamber to generate vapors in the upper portion thereof, means

on the cap forming a vapor chamber above said restricted chamber, and means comprising a perforated thimble placing the upper portion of the restricted chamber in communication with said vapor chamber.

8. A vaporizer of the class described comprising a large fluid container, means forming an elongated restricted fluid chamber in said container, means for electrically heating fluid in said chamber to generate vapors in the upper portion thereof, a vapor chamber above said restricted chamber, means comprising a perforated thimble placing the upper portion of the restricted chamber in communication with said vapor chamber, said vapor chamber having a discharge, and means comprising an openwork member for supporting a predetermined treating element in said vapor chamber in characterizing vapors discharged therefrom.
9. A vaporizer of the class described comprising a large fluid container, means forming an elongated restricted fluid chamber in said container, means for electrically heating fluid in said chamber to generate vapors in the upper portion thereof, a vapor chamber above said restricted chamber, means comprising a perforated thimble placing the upper portion of the restricted chamber in communication with said vapor chamber, said vapor chamber having a discharge, means comprising an openwork member for supporting a predetermined treating element in said vapor chamber in characterizing vapors discharged therefrom, and means detachably suspending the openwork member in said vapor chamber.
